LAMP SHADE

Jhi Hung Leung, Kowloon, Hong Kong, assignor to Star
Industrial Co., Ltd., Kowloon, Hong Kong

Filed Oct. 23, 1974, Ser. No. 517,439

Claims priority, application Great Britain Aug. 5, 1976

Term of patent 7 years

Int. Cl. D26—05

U.S. Cl. D48—16 D

FIG. 1

FIG. 4

FIG. 2

FIG.3

FIG. 5

FIG. 1 is a perspective view of the lamp shade showing my new design;

FIG. 2 is a plan view of the top thereof;

FIG. 3 is a horizontal section taken on the line 3—3 in FIG. 4;

FIG. 4 is a vertical section taken on the line 4—4 in FIG. 2; and

FIG. 5 is an enlarged side elevation of one of the transparent panels, the rest of the shade being omitted for convenience of illustration and purposes of disclosure.

I claim:

The ornamental design for a lamp shade, substantially as shown and described.
